UNITED STATES PATENT OFFICE.

ISAAC BELL RITTER, OF PHILADELPHIA, PENNSYLVANIA.

SWITCH.

SPECIFICATION forming part of Letters Patent No. 747,774, dated December 22, 1903.

Application filed July 8, 1903. Serial No. 164,644. (No model.)

To all whom it may concern:

Be it known that I, ISAAC BELL RITTER, a citizen of the United States, residing at Philadelphia, in the county of Philadelphia and State of Pennsylvania, have invented certain new and useful Improvements in Switches, of which the following is a specification.

My invention relates to improvements in railway-switches, and is particularly adapted to street-railways where a central slot between the tracks is used for the depending plow carried by the cars to enter and make contact with electrical conductors or to engage a cable.

15 The object of my invention is to provide a switch mechanism which will control the switch-tongues and the slot switch-bars in the central slot, giving them a positive and simultaneous movement and locking the same in either position—that is to say, when the switch is opened or closed.

My invention is provided with and operated by a pin located between the tracks, which is acted upon by an automatic switch-controller carried by the car, such as that shown and described in Letters Patent for "Automatic switch-controller," No. 692,050, dated the 28th day of January, A. D. 1902.

A further object of my invention is to have 30 the above-mentioned operating-pin concealed except when in operation. This is accomplished by the operating-pin being raised above the surface of the street by the wheel of an approaching car depressing a pin in the rail, and after the automatic switch-controller on the car shifts the switch to the desired position the car-wheel depresses a second pin, which causes the operating-pin to disappear.

40 A still further object of my invention is to provide a means of shifting the switch by a car coming from the opposite direction from where the central operating-pin is located. This consists of two pins, one in the main track and one in the branch track, and as the car approaches the switch the wheels will contact with the pin in that particular track and open the switch, so that the car may pass through it.

50 Referring to the drawings, Figure 1 illustrates a plan view of a switch, showing my

invention embodied therein. Fig. 2 is a side view of the same. Fig. 3 is a vertical sectional view on line 3 3, Fig. 1. Fig. 4 is a vertical sectional view on line 4 4, Fig. 1. 55 Fig. 5 is a view similar to Fig. 4, showing the parts in a different position. Fig. 6 is a vertical sectional view on line 6 6, Fig. 1. Fig. 7 is a vertical sectional view on line 7 7, Fig. 1. Fig. 8 is a perspective view of the levers 60 for operating the central operating-pin. Fig. 9 is a perspective view of one of the pins operated by the car-wheel.

In the drawings, A and A' represent the tracks on the main line, and A² and A³ represent the branch tracks.

A⁴ represents the switch-tongues, pivoted at a.

B represents the central groove for the plow carried by the car; B', the groove for the 70 branch track.

B² represents plates covering the space between the tracks and central grooves to protect the operating mechanism.

B³ and B⁴ are the slot switch-bars, pivoted at b to the frame W.

The vertical shafts C and C', as shown in Figs. 1 and 6, are adapted to rotate in bearings c. On the shafts C and C' are arms C², to which are pivoted the links C³ at c', and 80 at c² the said links are pivoted to the switch-tongues A⁴. The said arms also have links C⁴ pivoted to them at c³, which said links are pivoted to the slot switch-bars B³ and B⁴ at c⁴.

The links C⁴ are provided with extensions, 85 forming hooks C⁵, which engage the vertical shafts and prevent the shafts and links from turning too far. In Fig. 1 shaft C' is shown engaged by the hook C⁵, in which position the pivot-points c', c², c³, and c⁴ are all in line 90 with the vertical shaft C', forming a dead-center and locking the switch-tongue A⁴ and the slot switch-bar B⁴, so that they cannot be moved by any force applied directly to them.

The vertical shafts C and C' are rotated by 95 the following means: Each is provided with an arm C⁶, and pivoted to said arms are the rods C⁷ and C⁸, as shown in Fig. 6. The said rods are pivoted at their opposite ends to a lever C⁹, which is pivoted to and carried by 100 the lever C¹⁰, which is secured at C¹¹ to the rock-shaft C¹². It will readily be seen that

by rotating the said rock-shaft C^{12} the vertical shafts will be turned and operate the switch-tongues and the slot switch-bars.

As shown in Fig. 1, the vertical shaft C' is 5 locked by the links; but the shaft C is not locked. To hold the shaft C in its proper position, a weight C^{13} is provided which acts upon the rock-shaft C^{12} . The weight is carried by an arm C^{14} , pivoted to the frame W . (See Fig. 6.)

10 A link C^{15} connects the weight-arm and the lever C^{10} upon the rock-shaft C^{12} and holds said rock-shaft in its proper position. When the rock-shaft C^{12} is rotated in the direction of the arrow, the lever C^{10} raises the weight, and 15 when said lever C^{10} has moved the vertical shafts and the switch-tongues and slot switch-bars to the reverse position the weight will then hold them in said position.

The rock-shaft C^{12} is operated in the following manner: The said rock-shaft is provided with an arm D , as shown in Figs. 2 and 3, which is connected to an arm D' on a rock-shaft D^2 by a rod d . The rock-shaft D^2 is mounted in bearings d' , secured to the side 20 of the rails A' . The said shaft is also provided with an arm D^3 , having pivoted thereto a rod D^4 , which is pivoted at d^2 to the lower end of the central operating-pin E , as shown in Figs. 3, 4, and 5. The pin E passes up 25 through a disk F and is operated upon by the automatic switch-controller carried by the car. Said switch-controller, which is not shown in the drawings, may be of any form, but preferably a block suspended from the 30 car having a cam-surface the angle of which may be set so as to give the pin E a motion at right angles to the tracks A and A' when the said cam is brought in contact with the pin E by the moving car. The switch-controller is adapted to be set so as to move the 35 pin E in either direction, the effect of which being to open or close the switch. The motion received by the pin E is communicated to the rod D^4 . (Clearly shown in Fig. 3.) 40 Said rod is connected to the arm D^3 on the rock-shaft D^2 , which is connected by the arm D' , the rod d , and the arm D to the shaft C^{12} . The rock-shaft C^{12} communicates motion to the vertical shafts C and C' through the medium of the lever C^{10} , the lever C^9 , carried by 45 said lever C^{10} and rods C^7 and C^8 , which are connected to the said lever C^9 and to the said vertical shafts. The said vertical shafts are each provided with arms C^2 , which are connected to the slot switch-bars by the links C^4 and to the switch-tongues by the links C^8 , thereby operating said switch-tongues and 50 the slot switch-bars.

The disk F has a pin f , which is pivoted to 55 the disk-frame F' , held in the projection F^2 of the frame F^3 . The disk-frame F' is provided with an opening f' , the ends of which act as a stop to limit the movement of the pin E . (See Fig. 1.)

60 The pin E is provided with a head E' , having arms E^2 , which enter elongated openings e in the levers E^3 and E^4 . (Shown in Fig. 8.)

These levers are mounted upon a shaft E^5 , which is pivoted to the track A' , and a bar E^6 on the frame W . Said shaft E^5 is provided 70 with levers E^7 and E^8 , having a connecting-plate E^9 , upon which rests a pin E^{10} , which projects up through an opening in the track A' . This pin when acted upon by the car-wheel depresses the levers E^7 and E^8 and 75 raises the levers E^3 and E^4 , which raise the pin E up above the surface of the plates B^2 , so that it may be engaged by the car. A spring G acts upon an arm g on the shaft E^5 and tends to depress the levers E^3 and E^4 , 80 carrying the pin E . To hold the pin up against the action of said spring, I provide an extension g' on the lever E^4 , which is engaged, as shown in Figs. 4 and 5, by a projection g^2 on an arm G^2 on the shaft G^3 , pivoted in bearings 85 in the track A' and the bar E^6 . An arm G^4 , Fig. 2, on said shaft is engaged by the spring G , which tends to hold the arm G^2 in engagement with the lever E^4 . A rod G^5 is also pivoted to said arm G^4 , and at its opposite end it 90 is pivoted to an arm G^6 of the bell-crank lever G^7 on the shaft G^8 , which is mounted in a bearing g^3 on the track A' . As shown in Fig. 9, the shaft G^8 is provided with another arm G^9 , and between said arm and the arm G^{10} is a 95 bar G^{11} , supporting a pin G^{12} , projecting up through an opening in the track A' , and is acted upon by the car-wheel, which depresses it, and, as shown in Fig. 4, the arm G^2 is withdrawn from engagement with the lever E^4 , which is then acted upon by the spring G , and the pin E is depressed.

The switch-tongues and the slot switch-bars are also operated by the pins H and I . As shown in Fig. 7, the pin H is pivoted at h 105 to a lever J upon the shaft J' . The pin I is also pivoted to the said lever J at i . The said pins project up through openings in the rails and are engaged by the wheels of the car. The shaft J' is mounted in bearings J^2 , 110 Figs. 2 and 6, and is provided with an arm J^4 , which is connected by a rod J^5 to an arm J^6 on the rock-shaft C^{12} . It will be seen that a movement of either of the pins H or I will 115 operate the said rock-shaft C^{12} and the switch-tongues A^4 and the slot switch-bars B^3 and B^4 . As shown in Fig. 1, the plate B^5 is provided with a pin B^6 , which acts as a stop and holds the slot switch-bars in their proper positions. 120

The operation of my invention is as follows: The car approaching the switch from the left side of Fig. 1 depresses the pin E^{10} by the wheel passing over said pin. This causes the operating-pin E to be raised above the surface 125 of the plates B^2 . The automatic switch-controller upon the car is then set so that it will move the pin E and open the switch, so that the car may pass through in the desired direction. When the car-wheel strikes the pin G^{12} , the arm G^2 , supporting the operating-pin E , is withdrawn and said operating-pin is depressed, so the top of said pin will be flush with the surface of plates B^2 . As the 130

mechanism is constructed so as to lock the switch-tongues and slot switch-bars, a car returning through the switch could not open the same, as in the ordinary switch. Therefore 5 the pins H and I are provided, and the wheels of the car returning upon either the main track or the branch track A² and A³ will contact with one of the said pins and operate the switch, so as to open it and allow the car to 10 pass through the same.

Having thus described my invention, I claim and desire to secure by Letters Patent—

1. The combination, in a switch, of the 15 switch-tongues, two slot switch-bars one located at each side of the central slot, and means of throwing one of said slot switch-bars in operation when the switch-tongues are in one position and of throwing the other 20 one of said slot switch-bars in operation when the switch-tongues are in the opposite position, substantially as described.

2. The combination, in a switch, of the switch-tongues, slot switch-bars, vertical 25 shafts, arms on said shafts, links pivoted to said arms and the switch-tongues, links pivoted to said arms and the slot switch-bars and means of operating the said vertical shafts, substantially as described.

3. The combination, in a switch, of the switch-tongues, slot switch-bars, vertical shafts, arms on said shafts, links pivoted to said arms and the switch-tongues, links pivoted to said arms and the slot switch-bars, 35 projections forming hooks on said last-mentioned links adapted to engage the said vertical shafts and lock the switch-tongues and slot switch-bars, substantially as described.

4. The combination, in a switch, of the switch-tongues, slot switch-bars, vertical 40 shafts, arms on said vertical shafts, links pivoted between said arms and said switch-tongues, links pivoted between said arms and said slot switch-bars, a lever on each of said vertical shafts, a rod connected to each of said levers, a rock-shaft, and a lever on said rock-shaft adapted to impart motion through said rods to said vertical shafts, substantially as described.

5. The combination in a switch, of switch-tongues, slot switch-bars, a rock-shaft, vertical shafts, means of communicating motion from said rock-shaft to said vertical shafts, links pivoted to said vertical shafts and to 55 said switch-tongues, and links pivoted to said vertical shafts and to said slot switch-bars, substantially as described.

6. The combination, in a switch of slot switch-bars, a rock-shaft, vertical shafts, 60 means of communicating motion from said rock-shaft to said vertical shafts, links pivoted to said vertical shafts and to the slot switch-bars, substantially as described.

7. The combination, in a switch, of slot 65 switch-bars, a rock-shaft, vertical shafts, means of communicating motion from said rock-shaft to said vertical shafts, links piv-

oted to said vertical shafts and to the slot switch-bars, links pivoted to said vertical shafts and to the switch-tongues, rods pivoted 70 to said vertical shafts and to said rock-shaft, a weight adapted to act upon said rock-shaft, an operating-pin and means of communicating motion from said operating-pin to said rock-shaft, substantially as described. 75

8. The combination, in a switch, of an operating-pin, means of communicating motion from said operating-pin to the switch, a pin located in the track adapted to be depressed by the car-wheel and thereby raise the operating-pin above the top surface of the switch, and a pin located in the track adapted to be depressed by the car-wheel and depress the operating-pin, substantially as described. 80

9. The combination, in a switch, of an operating-pin, a disk carrying the same, levers engaging said pin, a shaft carrying said levers, an arm having a notch engaging one of said levers to lock said pin in the raised position, a shaft carrying said arm, a spring to 90 hold said arm and lever in engagement, a pin adapted to act upon the levers carrying the operating-pin, a pin adapted to act upon the notched arm and release the levers carrying the operating-pin and means of communicating motion from the operating-pin to the switch, substantially as described. 95

10. The combination, in a switch, of an operating-pin, an arm, a rod pivoted to said operating-pin and arm, a shaft carrying said 100 arm, an arm on the opposite end of said shaft, a rock-shaft, a rod and arms connecting the said first-mentioned shaft and rock-shaft, and means of communicating motion from the said rock-shaft to the switch-tongues and slot 105 switch-bars to operate the the same substantially as described.

11. The combination, in a switch, of an operating-pin, a disk, levers to raise and depress said operating-pin, a pin to raise said operating-pin, and a pin to depress said operating-pin, an arm and shaft connected to said operating-pin by a rod, or rock-shaft connected to the last-mentioned shaft by arms and a rod, a lever on said rock-shaft, a weight acting 110 upon one end of said lever, a lever pivoted to the last-mentioned lever, rods connected to the same, arms upon vertical shafts, vertical shafts, arms on the latter, links pivoted to said arms, switch-tongues and slot switch-bars to which said links are pivoted, substantially 115 as described.

12. The combination, in a switch, of a pin located in the main track, a pin located in the branch track, a lever to which said pins are 120 pivoted, a shaft carrying said lever, an arm on said shaft, a rod pivoted to said arm, an arm, a rock-shaft carrying said arm, and means of communicating motion from said rock-shaft to the switch-tongues and slot 130 switch-bars, substantially as described.

13. The combination, in a switch, of a pin located in the main track, a pin located in the branch track, a lever to which said pins are

pivoted, a shaft carrying said lever, an arm on said shaft, a rod pivoted to said arm, an arm, a rock-shaft carrying said arm, a lever on said rock-shaft, a weight to act upon one 5 end of said last-mentioned lever, a lever carried by the opposite end of said last-mentioned lever, rods pivoted thereto, vertical shafts, said rods pivoted to levers on said vertical shafts, arms on said vertical shafts, links pivoted thereto, switch-tongues and slot switch-bars, substantially as described.

14. The combination, in a switch, of an operating-pin, a disk, levers to raise and depress said operating-pin, a pin to raise said operating-pin, and a pin to depress said operating-pin, an arm and shaft connected to said operating-pin by a rod, or rock-shaft connected to the last-mentioned shaft by arms and a rod, 15 a pin located in the main track, a pin located

in the branch track, a lever to which said pins 20 are pivoted, a shaft carrying said lever, an arm on said shaft, a rod pivoted thereto, an arm on the said rock-shaft, a lever on said rock-shaft, a weight acting upon one end of said lever, a lever pivoted to the last-mentioned lever, rods connected to the same, 25 arms upon vertical shafts, vertical shafts, arms on the latter, links pivoted to said arms, switch-tongues and slot switch-bars to which said links are pivoted, substantially as de- 30 scribed.

In testimony whereof I affix my signature in presence of two witnesses.

ISAAC BELL RITTER.
